STATUETTE OR THE LIKE

Josephine M. Richardson, R.R. 5, Decatur Hi-Way
Airport, Decatur, Ind.

Filed Apr. 30, 1963, Ser. No. 74,678

Term of patent 14 years

(Cl. D29—23)

Fig. 2

Fig. 1

The back of the statuette is plain and unornamented.

I claim:

The ornamental design for a statuette or the like, as shown and described.
